W. T. POWELL

AUTOMATIC TELEPHONE SYSTEM

Filed July 1, 1919

UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

AUTOMATIC TELEPHONE SYSTEM.

Application filed July 1, 1919. Serial No. 307,915.

To all whom it may concern:

Be it known that I, WINFRED T. POWELL, a citizen of the United States, residing at Rochester, in the county of Monroe and 5 State of New York, have invented certain new and useful Improvements in Automatic Telephone Systems (Case 47), of which the following is a full, clear, concise, and exact description.

10 This invention relates to telephone systems, and more particularly to telephone systems employing automatic switches in completing connections between calling and called subscribers.

15 In systems of this character it has formerly been the practice to directly operate an automatic switch by impulses transmitted from a distant point and then to directly select the wanted line in the group 20 previously selected. This method of operation required group and line selecting mechanisms as well as "change-over" mechanisms, that is, means for disabling the group selecting mechanism while the line selecting mechanism is in operation.

25 One of the features of this invention is the provision of means whereby an automatic switch may be advanced a distance proportional to the number of impulses transmitted in several series.

Another feature of the invention is the provision of means whereby an automatic switch moves in the same direction in response to a plurality of impulses from a 35 distant point, the total number of steps taken by the automatic switch being equal to the sum of the impulses of the various series transmitted.

Another feature of the invention relates 40 to means for signaling a wanted telephone line.

An additional feature of the invention is the provision of circuits for testing a wanted line.

45 Fig. 1 of the drawings diagrammatically represents a portion of the telephone system employing the present invention, and shows a calling line extended through the brushes or wipers of a numerical switch 50 to a called line. The portion of the drawing included within the dotted circles represents impulse senders which may be of any of the well known types that have shunting springs for shunting the transmitter

during the transmission of impulses. A 55 push button is provided at each of the substations to control a break point in a conductor other than the talking conductors that is employed for testing and signaling the wanted line.

Fig. 2 of the drawings is a front view of the dial of the sender indicating that the sender is arranged to transmit impulses on the decimal basis in addition to other series of impulses, one having twelve impulses 65 in the series and the other twenty impulses.

Fig. 3 of the drawings is a schematic showing indicating that the switch, represented by the brushes 20, 21 and 22 of Fig. 1, has fifty-two terminals. This view 70 also indicates the various adjustments of dial of Fig. 2 to set the brushes of the switch in engagement with any of the desired lines.

The switches employed in this system are 75 of the well known rotary type, preferably provided with fifty-two terminals as mentioned which are arranged in an arcuate bank for engagement by brushes which are progressively advanced step-by-step by a 80 ratchet and pawl arrangement and are restored to normal by a well known release magnet. The release magnet employed in connection with the switch may be of any type which has a sluggish armature to control the holding dog. It should be stated that all of the terminals of the switch are 85 connected to outgoing lines. In the present arrangement the first terminal of the switch designated "trunk" in Fig. 3 is connected 90 to an outgoing trunk to a distant exchange. To select this trunk it is necessary only to remove the receiver from its switchhook whereupon the switch individual to the calling line will move to an off normal position 95 as will be described. The push button is then depressed to signal the distant exchange.

Although a dial sending any number of impulses may be employed in connection 100 with the present system, it is desirable in the present arrangement to employ a sender which sends series of twelve impulses and twenty impulses in addition to the decimal arrangement of impulsing now in use.

105 With this brief description of the apparatus employed, it is believed that the present invention will best be understood by describ-

- ing the method of establishing a connection between a calling subscriber at A and a called subscriber at B. When the calling subscriber at A removes his receiver from its switchhook, a stepping relay SR individual to this line is energized in a circuit extending from grounded battery, winding of the relay SR, ring conductor 1, primary winding of the induction coil at the substation through 5
- 10 the transmitter and impulse spring 2, tip side of the line 3, winding of the impedance coil 4, to ground. In response to the energization of the stepping relay SR, the motor magnet MM is operated over a circuit completed 15 from grounded battery, through its winding, armature and back contact, inner front contact and armature of the stepping relay SR, contact 4', off normal spring ON, left hand low resistance winding of the relay 5, to ground. The motor magnet MM is operated in this circuit and causes the numerical switch which it controls, to advance 20 one step to an off normal position in which it remains until the calling subscriber dials 25 a series of impulses.

In response to the first series of impulses, the stepping relay SR vibrates its armatures once for each impulse transmitted, and the motor magnet MM is operated in synchronism 30 with the stepping relay SR, over a circuit traceable from grounded battery, winding of the motor magnet MM, conductor 6, lower-most back contact and armature of the relay 7, conductor 8, right-hand back contact and armature of the stepping relay SR, contact 9 and off normal spring ON, winding of the relay 5, to ground. The motor magnet MM thus advances its numerical switch one step in response to each impulse 35 transmitted from the substation at A.

The lower winding of the relay 7 has previously been energized over a circuit completed from grounded battery, lower winding of the relay 7, contact 9 and off normal 40 spring, winding of relay 5, to ground. The energization of only the lower winding of the relay 7 will not cause this relay to attract its armatures, but will maintain these armatures in their alternate position whenever 45 attracted.

It will be noted that a circuit for the release magnet REL is closed in parallel with the operating circuit of the motor magnet MM just described, but since the armature 50 of the release magnet is sluggish, it will not be attracted during momentary energizations of the release magnet and therefore the numerical switch will not be released at this time.

60 In response to the next series of impulses, if the wanted substation is designated by a two-digit designation, the numerical switch under consideration will continue to be advanced in the same direction step-by-step in response to the impulses from the sender at

substation A, at the end of which series the switch will have a number of steps equal to the sum of impulses of the two series. If it is necessary to dial a third series of impulses, the numerical switch will continue 70 to be advanced in the same direction as in the case of the preceding series of impulses until the terminal of the wanted line is reached.

It now becomes necessary to test the wanted line to determine whether or not it is engaged, and if it is not engaged, to apply signaling current to it. These operations are accomplished in the following manner. The subscriber at A after having completed 80 the sending of the directive impulses, presses the push button 11, and thereby closes a circuit from grounded battery, winding of the ringing relay 12, upper winding of the electrically polarized relay 7, conductor 85 13, contacts of the push button 11, contact 14 and shunting spring of the sender, contact 2 of the impulse spring, tip conductor 3 of the line, winding of the impedance coil 4, to ground, and since the upper winding 90 of the relay 7 is energized in the same direction as the lower winding, this electrically polarized relay 7 attracts its armatures.

The relays 7 and 12 are energized in the circuit just described and attract their armatures to apply signaling current to the wanted line. At the lower armature and front contact of the relay 12, a circuit is closed from ground, over conductor 15, back contact, armature and winding of the magnet 95 16 of the ringing machine, to grounded battery. The ringing machine thereupon operates to induce an alternating current in a circuit extending from ground, lamp 17, secondary winding of the induction coil, 100 lamp 18, conductor 19, uppermost front contact and armature of the relays 12 and 7, brush 20 of the numerical switch through the closed impulse contacts of the sender 105 through the condenser and bell of the substation at B, ring conductor of the called line, brush 21 of the numerical switch, inner-most front contacts and armatures of relays 7 and 12, to ground. The relay when 110 energized as described above is maintained 115 energized during conversation through its lower winding.

Let it be assumed that the wanted subscriber is busy when the brushes 20, 21 and 120 22 of the numerical switch were placed in engagement with the terminals of this line. Under this assumption a guarding ground will be present on the test terminal 23 of the wanted line, which is applied through the low resistance winding of the relay 5, an 125 off normal spring and contact similar to 9, a conductor similar to 24 of the other numerical switch that is in engagement with the wanted line, to the test terminal 23. Under this condition the upper winding of 130

the electrically polarized relay 7 may be energized from this ground on test terminal 23, test brush 22, inner-most lower back contact and armature and upper winding of the relay 7, conductor 13, push button 11, contact 14 and shunting spring of the sender, the transmitter and through switchhook contacts; primary winding of the induction coil at the substation A, winding of the stepping relay SR, to grounded battery. In this instance the windings of the electrically polarized relay are energized in opposite directions so that this relay does not attract its armatures, and ringing current is not applied to the wanted line. The relay 12, however, which is energized whenever the push button 11 is depressed, closes a circuit from ground, lower armature and front contact of relay 12, conductor 15, armature, back contact and right hand winding of relay 5, to grounded battery. In this circuit the relay 5 rapidly vibrates its armatures, thus inducing a current which causes a tone in the receiver of the calling subscriber at A in a circuit extending from ground, left hand winding of the relay 5, off normal spring and contact similar to 9, conductor similar to 24 and test terminal 23 of the wanted line at the switch already in engagement with this line, test brush 22 of the numerical switch individual to the calling line, inner lower back contact and upper winding of the relay 7, conductor 13, push button 11, contact 14, shunting spring of the sender through the condenser and secondary winding of the induction coil at the substation, through the receiver and switchhook contacts, primary winding of the induction coil, stepping relay SR, to grounded battery.

Battery is supplied to the calling party through the windings of stepping relay SR and impedance coil 4. Talking battery for the called subscriber is supplied through the stepping relay and impedance coil individual to his line. It should be noted that as soon as the calling subscriber operated the relay 7 in testing the called line, the impedance coil 27 is bridged across brushes 20 and 21 to close a circuit for energizing a stepping relay corresponding to SR, and the motor magnet of the switch individual to called line is operated to cause the switch to advance to an off normal position where it remains during the conversation. With the called subscriber's switch in an off normal position, ground is applied to the test terminal of the called line, through the low winding of relay 5, to apply a guarding potential to this terminal.

When the calling subscriber replaces his receiver on the switchhook at the close of the conversation or because the wanted line is busy, the energizing circuit of the stepping relay SR is interrupted and causes this

relay to retract its armatures. The release magnet REL is now energized for a long interval in the circuit previously traced from grounded battery, winding of the release magnet, conductor 8, outer back contact and armature of the stepping relay SR, contact 9 and off normal spring, left hand winding of the relay 5, to ground. The release magnet in this instance attracts its sluggish armature 10 and thereby releases the holding dog of the switch which returns to normal position in the well known manner. The apparatus and circuits are now in condition for operating on another call.

In accordance with an additional feature of the present system, conference calls, that is, calls between three or more parties, may be established without the intervention of an operator. The conference calls are established in the following manner. Each of the conferees at the time when a conference is to be held, removes his receiver from the switchhook at his substation whereupon the switch individual to his line moves to its first set of terminals corresponding to those designated "trunk" in Fig. 3, and he then presses the push button located at his station as if to signal a wanted party. In providing for this arrangement, it is only necessary that the first terminals of the connector switches, that is, the terminal designated "trunk" in Fig. 3, should not be connected to any outgoing line. The multiple connections between these first terminals at all the switches are the same as any subscriber's line. In disestablishing the connection it is only necessary to have the parties replace their receivers on the switchhooks as is the case of an ordinary call.

What I claim is:—

1. In a telephone system, incoming lines, a plurality of outgoing lines, automatic switches for interconnecting said incoming lines with any of said outgoing lines, a test conductor for each of said outgoing lines, means for applying a busy condition to the test conductor of a busy line, and a busy signal arranged to be transmitted to an incoming line when said line is extended to a busy outgoing line, said busy signal being transmitted over a portion of the test conductor of said busy outgoing line.

2. In a telephone system, incoming lines, a plurality of outgoing lines, automatic switches for interconnecting said incoming lines with any of said outgoing lines, a test conductor for each of said outgoing lines, means for applying a busy condition to the test conductor of a busy line, and a busy signal arranged to be transmitted to an incoming line when said line is extended to a busy outgoing line, said busy signal being transmitted over a portion of the test conductor of said busy outgoing line and a talking conductor.

3. In a telephone system, incoming lines, a plurality of outgoing lines, automatic switches for interconnecting said incoming lines with any of said outgoing lines, means for applying a busy condition to the test conductor of a busy line, and a busy signal arranged to be transmitted to an incoming line when said line is extended to a busy outgoing line, said busy signal being initiated and continued over a portion of the test conductor of said busy outgoing line.
4. In a telephone system, incoming lines, a plurality of outgoing lines, automatic switches for interconnecting said incoming lines with any of said outgoing lines, means including a manually controlled mechanism for testing said outgoing lines, means for applying a busy condition to the test conductor of a busy line, and a busy signal arranged to be transmitted to an incoming line when said line is extended to a busy outgoing line, said busy signal being initiated by said manually controlled means and transmitted over a portion of the test conductor of said busy outgoing line.
5. In a telephone system, an incoming line, an impulse transmitter associated with said line, a plurality of outgoing lines, an automatic switch, means for receiving several series of impulses and for advancing said switch a distance proportional to the number of impulses received to seize a wanted outgoing line if idle and testing means including an electrically polarized relay for testing said outgoing lines.
6. In a telephone system, a plurality of telephone lines, an impulse transmitter and a progressively movable switch associated with each telephone line, means associated with each switch for receiving several series of impulses from its associated impulse transmitter and for advancing said switch a distance proportional to the number of impulses received to seize a wanted outgoing line and means responsive to such seizure for operating the switch of the wanted outgoing line to render said line unselectable.
7. In a telephone system, a plurality of telephone lines, an impulse transmitter and an individual progressively movable switch for each telephone line, each of said switches having a normal position, means associated with each automatic switch for receiving several series of impulses and for advancing said switch a distance proportional to the number of impulses received to seize a wanted outgoing line and means responsive to such seizure and independent of the response of the wanted party for advancing the switch individual to the wanted line to an off-normal position.
8. A telephone system including a subscriber's line, an automatic adding-type connector switch individual to said subscriber's line controlled over the two sides of the subscriber's line in series, a single row or level of bank contacts for said automatic switch, other subscribers' lines terminating in said bank contacts, subscriber controlled means for said switch governed over the two talking conductors of said telephone lines in series for connecting said first subscriber's line to any one of said other subscribers' lines, subscriber-controlled means for ringing the called substation, and automatic means for moving said switch to normal position.

In witness whereof, I hereunto subscribe my name this 30th day of June, A. D. 1919.

WINFRED T. POWELL.
